UNITED STATES PATENT OFFICE.

BENJAMIN J. BUELL, OF READING, PENNSYLVANIA.

CAR-REPLACER CLAMP.

Specification of Letters Patent. Patented Oct. 15, 1918.

1,281,505.

Application filed June 4, 1918. Serial No. 238,075.

To all whom it may concern:

Be it known that I, BENJAMIN J. BUELL, a citizen of the United States, and a resident of Reading, in the county of Berks and 5 State of Pennsylvania, have made and invented certain new and useful Improvements in Car-Replacer Clamps, of which the following is a specification.

My invention relates to holding devices or 10 clamps commonly referred to as car replacer clamps, and which are designed for use with car replacers or rerailers; the purpose of such clamps being to fasten the replacer to the rail and hold the same properly and securely in place during the replacing or rerailing operation and while a derailed car wheel or wheels are being replaced upon the rails of a railway track, thus avoiding the necessity of securing the 15 replacer in place by the use of spikes driven into the ties and at the same time providing means whereby the replacer may be easily and quickly put in place and clamped to the rail, and as readily removed from the rail 20 at the completion of the rerailing operation.

The objects of my invention are to provide a car replacer clamp for the purpose stated in which the clamp is tightened to thereby secure the replacer proper in place 30 relatively to a rail by means of a wedge movable transversely to a clamping bar extending transversely to and beneath the rail, and having a hook at one end adapted to engage the base of a car replacer, an abutment 35 at the other end against which one edge of the wedge acts, and a movable block with which the other edge of said wedge engages; to provide a clamp in which the clamping bar is bent so that the end thereof 40 at which the wedge operates will be somewhat above the upper surface of the ties upon which the rail rests; to provide a clamp in which the wedge referred to is permanently connected with or secured to the clamping 45 bar; and to provide various particular features of advantage in and relating to clamps of the class above referred to.

With the above and other objects in view, my invention consists in the improved car 50 replacer clamp illustrated in the accompanying drawing and hereinafter described and claimed, and in such variations and modifications thereof as will be obvious to those skilled in the art to which my invention relates.

In the drawing accompanying and forming a part of this specification and wherein the preferred embodiment of my invention is illustrated:

Figure 1 is a view showing my improved 60 car replacer clamp in use and arranged to hold an ordinary form of car replacer to a rail;

Fig. 2 is a view showing a section upon a 65 vertical transversely extending plane indicated by the line 2—2, Fig. 1;

Fig. 3 is a view showing the clamp and 70 replacer shown in Fig. 1 in elevation, and as seen from a position to the left of said figure;

Fig. 4 is a view showing a section taken upon a vertical longitudinally extending plane indicated by the line 4—4, Fig. 2;

Fig. 5 is a view showing a movable block 75 which forms a part of my device, in perspective; and

Fig. 6 is a view showing the clamping bar of my device in perspective.

Referring to the drawing, the reference 80 numeral 7 designates ties of a railway track, and 8 one of the rails thereof; while the reference numeral 9 is applied to a car replacer designed to be clamped to the rail 8 by my improved replacer clamp, the car replacer resting upon and being supported by the 85 ties and the inner wall thereof being usually cut away so that it may extend slightly over the base of the rail, as shown in Fig. 2. The replacer proper is ordinarily provided 90 with spacing lugs 10 upon its inner side the extremities of which engage the web of the rail, as also shown in Fig. 2, to thereby space the replacer as a whole slightly away from the rail and insure the proper location 95 of the replacer relatively to the rail when clamped thereto.

My improved replacer clamp may be employed for securing any kind of a car replacer to a rail, and may be used either with inside or outside replacers. The replacer shown in the drawing, however, is an inside replacer, *i. e.*, a replacer designed 100 to be secured upon the inside of a rail and to replace that one of the wheels of a car, locomotive, or other vehicle, which is between the two rails of the track. The replacer illustrated is a double-ended replacer, and is capable of use in replacing a vehicle wheel approaching it from either direction, although my invention may obviously be 110

applied equally well to a double-ended or to a single-ended replacer.

Fig. 1 illustrates a car wheel approaching the replacer, and which wheel is to be lifted from the ties upon which it rests and replaced upon the track by the replacer. During this replacing operation the tread T of the car wheel will first engage an upwardly projecting ridge 11 of the replacer 9, and shortly after this the flange F of the wheel will enter and begin to travel along a groove 12 provided in the replacer. The height of the ridge 11 decreases gradually, or, as otherwise stated, the bottom wall of 15 the groove 12 rises more rapidly than the upper wall of the ridge. As the wheel travels up the tread engaging ridge 11 of the replacer it soon reaches a point where the flange engages the bottom wall of the groove 20 12, after which the weight upon the wheel is transferred from the tread to the flange and is thereafter supported by the flange. The ridge and the bottom wall over the groove merge with each other at about the 25 point 13, and beyond this point toward the center thereof the upper surface of the replacer is so shaped as to provide a downwardly inclined surface sloping toward the head of the rail; the approximate form of 30 this surface at the central portion of the rerailer where it attains its maximum inclination being shown at 14, Fig. 2. Before the wheel reaches the highest point of the replacer, however, it will ordinarily have 35 moved sidewise and slid down the inclined surface thereof at some place between the point 13 and the middle portion of the replacer, and onto the rail, as shown in Fig. 2. As above stated, however, my improved 40 replacer clamp is capable of use with any form of replacer, and is not necessarily limited to use with replacers having the upwardly projecting tread engaging portion 11, the depressed flange groove 12, and the 45 laterally inclined portion 14, present in the replacer illustrated.

My improved replacer clamp comprises a clamping bar shown by itself in Fig. 6, and to which the reference numeral 15 is applied; the said bar being preferably of channel form and having depending sides 16 to thereby secure the requisite strength without unduly increasing the weight thereof. These side flanges extend to the ends 50 of the bar, as best shown in Fig. 6, and the said side flanges and the body of the bar are formed into an upwardly extending hook 17 at the inner end of the bar, which hook is adapted to engage the inner edge 55 of the base of the replacer 9, which is ordinarily provided with a flange as shown, to thereby force the lugs 10 of the replacer against the web of the rail and hold the replacer in place relative to the rail, as illustrated in Figs. 1 and 2 of the drawing.

The outer end of the clamping bar 15 is provided with an abutment 18 extending upward from the bar, which abutment is provided with a groove 19 in the outer wall 20 of which is inclined, as best shown in Fig. 1. The clamping bar 15 is bent slightly at about its middle portion, so that the two ends thereof extend at a slight angle to each other, this feature being adopted in order that the outer or left-hand end of the clamping bar may extend upwardly at a slight angle; so that a wedge 22 located at the outer end of the bar will be disposed slightly above the plane of the upper surface of the ties 7 and the wedge more conveniently driven into place in clamping the replacer to the rail, or loosened preparatory to removing the replacer clamp and replacer after the rerailing operation has been accomplished, than would be the case if the clamping bar were straight.

The wedge 22 above referred to is movable transversely to the clamping bar 15 in fastening the replacer to the rail and in releasing the replacer. This wedge is shown as provided with an inner edge 23 which extends substantially at right angles to the bar 15, and with an outer edge 24 which is inclined relatively to the clamping bar and co-operates with the inclined wall 20 of the abutment 18, as best shown in Fig. 1. The outer inclined edge of the said wedge therefore moves along the groove 19 in securing the replacer to the rail or in releasing the replacer, and the inner edge 23 of said wedge also moves in a groove 25 provided in a block 26 carried by and movable longitudinally of the clamping bar 15; and this block is preferably and is shown as provided with an overhanging ledge 27 adapted to fit over the base of the rail, as best shown in Fig. 2.

The clamping bar 15 is provided with a longitudinally extending slot 32, and the block 26 is provided with a depending neck 28 of such a size that it may rotate within the slot 32 as well as move longitudinally thereof. The lower end of the neck 28 is connected with a transversely extending head 29, the width of which is not greater than the width of the slot 32, and the free ends of which overlie the edges of the slot when the parts are assembled, as shown in Fig. 4. It therefore follows that when the block 26 is turned so that the head 29 extends longitudinally of the slot 32, the head may enter the slot; after which the block as a whole may be turned through an angle of 90°, to thereby bring the head 29 into the position shown in Figs. 2 and 4, in which the head extends transversely to the slot and prevents the block from becoming disengaged from the bar by the action of the wedge.

The slot 32, neck 28, and head 29, obvi-

ously provide means for both guiding the block 26 and keeping it in sliding engagement with the bar during its movements longitudinally of the clamping bar, and for retaining the said block in place relatively to the bar as the wedge 22 is driven in place between the block and the abutment 18; during which operation the block 26 will be forced against one edge of the base of the rail and the replacer 9 will be drawn into firm engagement with the rail through the hook 17 at the inner end of the clamping bar, as will be understood.

My improved replacer clamp is preferably provided with means for preventing the wedge from becoming separated from the clamping bar, or, as otherwise expressed, for maintaining the bar and wedge permanently associated with each other, so that the entire clamp forms a single unitary structure. The preferred form of means for thus holding the wedge permanently connected with the bar is shown as comprising a slot 30 formed in the wedge and located adjacent its inclined edge 24, and a pin, bolt, or equivalent securing member 31 which extends through a hole provided in the bar 15, and through the slot 30; from which it follows that the bar and wedge are prevented from becoming separated from each other, and the inclined edge 24 of the wedge is kept in a position adjacent the inclined wall 20 of the abutment 18, as the wedge moves transversely to the clamping bar during the clamping or releasing operations.

Having thus described and explained my invention, I claim and desire to secure by Letters Patent:

1. A replacer clamp of the class described comprising a clamping bar having an upwardly extending hook at one end; a block carried by said bar and movable longitudinally thereof, and which block is provided with a groove; a wedge having one edge extending substantially at right angles to said bar and which edge is adapted to move within said groove, and a second edge inclined with reference to said bar; and an abutment located at the other end of said bar and having a groove provided with an inclined wall with which the inclined edge of said wedge engages.

2. A replacer clamp of the class described comprising a clamping bar having an upwardly extending hook at one end, and an upwardly extending abutment provided with a groove at its other end; a block carried by said bar and movable longitudinally thereof and having a groove disposed opposite the groove in said abutment; means carried by said block and engaging said bar guiding said block in its movements, and for preventing the same from leaving said bar; and a wedge movable transversely to said bar and the side edges of which are adapted

to engage and move in the grooves aforesaid in said abutment and in said block.

3. A replacer clamp of the class described comprising a clamping bar having an upwardly extending hook at one end, and an upwardly extending abutment provided with a groove at its other end; a block carried by said bar and movable longitudinally thereof and having a groove disposed opposite the groove in said abutment; means carried by said block and engaging said bar for guiding said block in its movements, and for preventing the same from leaving said bar; a wedge movable transversely to said bar and the side edges of which are adapted to engage and move in the grooves aforesaid in said abutment and in said block; and means carried by said bar and engaging said wedge for keeping such wedge permanently associated with said bar.

4. A replacer clamp of the class described comprising a clamping bar having an upwardly extending hook at one end; a block carried by said bar and movable longitudinally thereof; a wedge having one edge extending substantially at right angles to said bar and adapted to engage said movable block, and a second edge inclined with reference to said bar, and which wedge is provided with a longitudinally extending slot located adjacent its inclined edge; an abutment located at the other end of said bar and having a groove provided with an inclined wall with which the inclined edge of said wedge engages, and a pin extending across the groove in said lug and through the slot in said wedge to thereby prevent said wedge from becoming separated from said bar.

5. A replacer clamp of the class described comprising a clamping bar having an upwardly extending hook at one end, and an upwardly extending abutment provided with a groove the outer wall of which is inclined at its other end; a block carried by said bar and movable longitudinally thereof and having a groove disposed opposite the groove aforesaid in said abutment; means carried by said block and engaging said bar for guiding said block in its movements and for preventing the same from leaving said bar; and a wedge movable transversely to said bar and having an inclined edge adapted to engage and move in the groove in said abutment, and a second edge extending substantially at right angles to said bar and adapted to engage and move in the groove in said block.

6. In a replacer clamp of the class described, a clamping bar having a longitudinally extending slot; a block having a neck adapted to rotate within and move along said slot, and a head greater in length but of less width than said slot located at the free end of said neck, and which head

is adapted to hold said block in sliding engagement with said bar; a hook at one end of said bar; and a wedge at the other end of said bar and movable transversely thereto, and which wedge is adapted to act upon said block.

7. In a replacer clamp of the class described, a clamping bar having a longitudinally extending slot; a block having a neck adapted to rotate within and move along said slot, and a head greater in length but of less width than said slot located at the free end of said neck and which head is adapted to hold said block in sliding engagement with said bar; said block having also a groove extending parallel with said head, and an overhanging ledge located upon the side thereof opposite said groove and extending parallel with said head and groove;
- 10 a hook at one end of said bar; and a wedge at the other end of said bar and movable transversely thereto, and the edge of which wedge fits within the groove aforesaid of said block.
- 15 8. A replacer clamp of the class described comprising a clamping bar having an upwardly extending hook at one end and an abutment at its other end, and which bar is bent so that the ends thereof extend at an angle to each other; a block carried by said bar and movable longitudinally thereof, and which block is provided with a groove; a wedge movable transversely to said bar and the edges of which move within said groove and within a second groove provided in said abutment, and which wedge is provided with a longitudinally extending slot; and a holding member carried by said bar and extending into said slot to thereby prevent said wedge from becoming separated from said bar.
- 20
- 25
- 30

bar and movable longitudinally thereof; a wedge movable transversely to said bar and acting between said abutment and said block; and means carried by said bar and engaging said wedge to prevent the same from becoming separated from said bar.

9. A replacer clamp of the class described comprising a clamping bar having an upwardly extending hook at one end and an abutment at its other end, and which bar is bent so that the ends thereof extend at an angle to each other; a block carried by said bar and movable longitudinally thereof, and which block is provided with a groove; a wedge movable transversely to said bar and the edges of which move within said groove and within a second groove provided in said abutment, and which wedge is provided with a longitudinally extending slot; and a holding member carried by said bar and extending into said slot to thereby prevent said wedge from becoming separated from said bar.

Signed at Reading, in the county of Berks and State of Pennsylvania, this 31st day of May, A. D., 1918.

BENJAMIN J. BUELL.
